INSULATED SERVING BUCKET

David L. Painter, Evanston, Ill., assignor to West Bend
Aluminum Co., West Bend, Wis., a corporation of Wisconsin

Application March 17, 1958, Serial No. 50,065

Term of patent 14 years

(Cl. D58—17)

FIG. 1

FIG. 2

FIG. 4

Fig. 1 is a view in front elevation of an insulated serving bucket showing my new design, the back thereof being identical;

Fig. 2 is a top plan view thereof;

Fig. 3 is a sectional view taken on the line 3—3 of Fig. 2; and

Fig. 4 is a fragmentary view in side elevation taken on the line 4—4 of Fig. 1, both sides being identical.

I claim:

The ornamental design for an insulated serving bucket, substantially as shown.
